CABLE RETAINER OR THE LIKE

Howard N. La Pierre, 14634 Hawes St.,
Whittier, Calif. 90604

Filed May 23, 1966, Ser. No. 2,408

Term of patent 14 years

(Cl. D54—1)

FIG. 1.

FIG. 2.

FIG. 3.

FIG. 4.

FIG. 6.

FIG. 5.

FIG. 1 is a plan view of a cable retainer or the like, showing my new design;

FIGS. 2, 3, 4 and 5 are elevational views thereof, taken respectively from the right, from above, from below, and from the left of FIG. 1; and

FIG. 6 is a perspective view thereof.

The cable attachment screw and support member shown in dotted outline are for illustrative purposes only.

I claim:

The ornamental design for a cable retainer or the like, substantially as shown and described.
